INVENTOR:
JOHN O. OLSON,

By Whitley and Ruckman

ATTORNEYS.

UNITED STATES PATENT OFFICE.

JOHN OTTO OLSON, OF ST. PAUL, MINNESOTA.

BOILER FOR HEATING SYSTEMS.

Application filed May 7, 1924. Serial No. 711,601.

My invention relates to boilers for heating systems and has for an object the provision of a boiler in which the heating medium, consisting of either water or steam, is subjected to an extended heating action in the combustion chamber. I accomplish the objects of my invention by the provision of a spiral member or coil placed above the fire-pot of the boiler and through the entire length of which the heating medium is compelled to travel so as to be subjected to a prolonged heating action without liability of dead pockets forming.

The full objects and advantages of my invention will appear in the detailed description thereof, and the novel features embodied in my inventive idea will be particularly pointed out in the claims.

In the accompanying drawings, which illustrate a practical embodiment of my invention,

Fig. 1 is a view of the boiler mostly in vertical central section.

Fig. 2 is a view in section on the line 2—2 of Fig. 1. Fig. 3 is a view in section on the line 3—3 of Fig. 1. Fig. 4 is a view in section on the line 4—4 of Fig. 1. Fig. 5 is a view in section on the line 5—5 of Fig. 1.

Referring to the construction shown in the drawings, the boiler includes a fire-pot 10 located within the inner wall 12 of a double-walled member having an outer wall 14, these two walls being arranged concentrically and enclosing an annular water chamber 16. Underneath a grate 18 at the bottom of the fire-pot is an ash-pit 20 provided with a door 22. Associated with the upper end of the fire-pot is a charging door 24. The double-walled member at its forward portion is of reduced height to provide for the charging door 24, and is of reduced depth to provide for a clinker-door 26. The double-walled member is entirely closed at its bottom, and is closed at its top except for a rear opening formed by an outwardly-bulged portion 28 of the outer wall 14 and an inwardly-bulged portion 30 of the inner wall 12, these bulged portions at their upper ends being enlarged interiorly to provide an annular flange 32. The portion 28 is turned outwardly so as to form a horizontal shoulder 34. A hollow spiral member 36 is provided at the outer end of its coil with a vertically extending tube 38 and at its inner end with a vertically-extending tube 40. The lower end of the tube 38 is rabbeted

to fit together with the flange 32. Above the member 36 in the embodiment shown is a second hollow spiral member 42 provided at its outer end with a vertically-extending tube 44 having rabbeted connection at its lower end with the upper end of the tube 38 and provided at its inner end with a tube 46 having rabbeted connection at its lower end with the upper end of the tube 40. The members 36 and 42 are flattened so that the coiled pipe which is produced is elongated in cross-section vertically. Having rabbeted connection with the upper end of the tube 44 is a cover-plate 48. A rod 50 extends through this cover-plate and through the shoulder 34. The spiral members are enclosed in a sheet metal casing 52 secured around the same, as shown in Fig. 4. At the upper end of the boiler is a chamber 53 in a horizontal casing 54 having a number of vertical smoke flues 56 arranged around the center thereof and extending therethrough so as to be open at top and bottom. The upper end of the tube 46 has a rabbeted connection with the lower wall of the casing 54 and the smoke flues 56 are arranged around this connection. A bottom plate 60 has rabbeted connection with the lower end of the tube 40 and a rod 62 extends centrally through the plate 60 and through the upper wall of the casing 54. A dome 64 is placed over the smoke flues 56 and a smoke-pipe 66 leads from the upper end of said dome. The front of the boiler is provided with clean-out doors 68 and 70 located slightly above the spiral members 36 and 42, respectively. Return pipes 72 for the heating medium lead into the chamber 16, while outlet pipes 74 lead from the chamber 53.

The operation and advantages of my invention will be readily understood in connection with the foregoing description. While I have shown two spiral members in the combustion chamber above the fire-pot, it will be understood that one or more of these members may be employed as desired. These spiral members may be cast or may be constructed of sheet metal and they take their supply of the heating medium at the back of the fire-pot, this medium being compelled to travel through the entire length of the coils before it enters the upper chamber of the boiler. While my invention is shown more particularly in connection with boilers for hot-water heating systems, it will be under-

stood that it may be used in connection with boilers for steam-heating systems. In the latter case the dome would be made larger to provide ample steam-carrying capacity. As 5 distinguished from boilers having flat sections for the heating medium, my boiler provides for longer travel of the heating medium and more surface is exposed to the fire, thereby reducing the quantity of fuel required. Also the circulation is positive and 10 rapid because friction is reduced to a minimum and dead pockets are eliminated. Furthermore, there is less opportunity for soot to collect and less tendency to reduce the 15 draft.

I claim:

1. A boiler for heating systems comprising an annular member having inner and outer walls, the inner wall forming a fire 20 pot, said inner and outer walls being spaced from each other and joined at their lower and upper ends to form a chamber, the upper end of said annular member having an outlet opening, a horizontally disposed hollow spiral member above said fire pot having its outer end connected with said outlet opening, a second horizontally disposed hollow spiral member above said first spiral member, the outer ends of the spiral members fitting together and their inner ends fitting together, an outlet pipe, and means 25 connecting said pipe and the inner end of said second spiral member.

2. A boiler for heating systems comprising 30 an annular member having inner and outer walls, the inner wall forming a fire pot, said inner and outer walls being spaced from each other and joined at their lower and upper ends to form a chamber, an inlet

pipe leading into said chamber, the upper 40 end of said outer wall having an outward bulge and the upper end of said inner wall having an inward bulge cooperating with said outward bulge to form an outlet opening, a horizontally disposed hollow spiral member above said fire pot having its outer end connected with said outlet opening, a second horizontally disposed hollow spiral member above said first spiral member, the outer ends of the spiral members fitting together and their inner ends fitting together, an outlet pipe and means connecting said pipe and the inner end of said second spiral member. 45 50

3. A boiler for heating systems comprising 55 an annular member having inner and outer walls, the inner wall forming a fire pot, said inner and outer walls being spaced from each other and joined at their lower and upper ends to form a chamber, an inlet pipe leading into said chamber, the upper end of said outer wall having an outward bulge and the upper end of said inner wall having an inward bulge cooperating with said outward 60 bulge to form an outlet opening, a horizontally disposed hollow spiral member above said fire pot having its outer end connected with said outlet opening, a second horizontally disposed hollow spiral member above 65 said first spiral member, the outer ends of the spiral members fitting together and their inner ends fitting together, a casing above said second spiral member connected with the inner end thereof, and an outlet pipe leading from said casing. 70 75

In testimony whereof I hereunto affix my signature.

JOHN OTTO OLSON.
